(57) **CLAIM**

The ornamental design for a wind chime, as shown and described.

DESCRIPTION

FIG. 1 is a front, right and top perspective view of a first embodiment of a wind chime, showing my new design; FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion 9 shown in FIG. 1;

FIG. 10 is an enlarged view of portion 10 shown in FIG. 1;

FIG. 11 is a front, right and top perspective view of a second embodiment of a wind chime;

FIG. 12 is a rear, left and bottom perspective view thereof;

FIG. 13 is a front view thereof;

FIG. 14 is a rear view thereof;

FIG. 15 is a left side view thereof;

FIG. 16 is a right side view thereof;

FIG. 17 is an enlarged top plan view thereof;

FIG. 18 is an enlarged bottom plan view thereof;

FIG. 19 is an enlarged view of portion 19 shown in FIG. 11; and,

FIG. 20 is an enlarged view of portion 20 shown in FIG. 11. The dot-dash broken lines depict the boundaries of the enlargements that form no part of the claimed design.

1 Claim, 20 Drawing Sheets
